Design No 743.

Benjamin Wandwell's Design for Stone.

Patented Nov. 20 1855.

Des. 743

Benjamin Wardwell of Fall River, Mass.
Letters Patent No. 743 Dated Nov. 26, 1855.

The Schedule referred to in these Letters Patent and making part of the same.

To all whom it may concern,

Be it known, That I, Benjamin Wardwell of Fall River in the county of Bristol and State of Massachusetts, have invented or produced a new and original design for a stove and I do hereby declare that the following is a full, clear, and exact description of the same, reference being had to the annexed drawings, making a part of this specification in which

Fig. 1, is a front view of the lower part of a stove, showing my design.

Fig. 2, is a plan or top view of do.

Fig. 3, is a section of the cylindrical portion of do.

Similar letters of reference indicate corresponding parts in the several figures.

A, represents the hearth or base of the stove which is of oval or elliptical form and

is a wreath or border B, around its edge, said wreath or border being raised or in relief, and formed of a series of semi circular beads (c), placed side by side; the ends of the beads at their points of connection having ornaments (b) attached - every alternate one being larger than the intermediate ones, as shown clearly in

Fig. 2.

C, represents the lower part of the stone which is attached to the base A. This part is of cylindrical form and rests upon a concave circular projection D, has a series of pointed sharp ornaments (e), upon it as shown in Fig. 1.

The front of the cylinder C, has two doors E, E, on each of which there are three pillars (f), the upper ends of which are connected by arches (g) and between the pillars there are ornaments (h). The pillars and arches are encircled by a border R, formed of semi circular beads (i) with ornaments (j) at their points of connection, see fig. 1. The body of the cylinder C, is pointed as shown in fig. 3, each hand (k) has two pillars (l), upon it the upper ends of the pillars having a gothic arch (m) upon them, see fig. 3.

The cylinder C, has a rim or projection (l) on its upper end, on which rim or projection a perpendicular wreath (n) is formed, said wreath having ornaments (o) attached as shown in fig. 2.

What I claim as new and desire to secure by letters patent is,

The border B, on the edge of the base A; the borders E, and other embellishments on the doors E, E, the wreath (n) on the rim or projection (l) of the cylindrical portion C, of the stone and the embellishments on the pillars (k) on the cylindrical portion C, when the above parts are arranged as shown to form an ornamental design for a stove.
